UNITED STATES PATENT OFFICE.

RICHARD T. GRADY, OF SAN DIEGO, CALIFORNIA.

DESIGN FOR A LANTERN.

56,920.

Specification for Design.

Patented Jan. 18, 1921.

Application filed July 22, 1920. Serial No. 398,326. Term of patent 14 years.

To all whom it may concern:

Be it known that I, RICHARD T. GRADY, a citizen of the United States, residing at San Diego, in the county of San Diego and State of California, have invented a new, original, and ornamental Design for a Lantern, of which the following is a specification, reference being had to the accompanying drawing, forming part thereof.

The figure is a perspective view of a lantern showing my new design.

I claim—

The ornamental design for a lantern as shown.

RICHARD T. GRADY.
